UNITED STATES PATENT OFFICE.

CHARLES W. KIRSCH, OF STURGIS, MICHIGAN, ASSIGNOR TO KIRSCH MANUFACTURING CO., OF STURGIS, MICHIGAN, A CORPORATION OF MICHIGAN.

CURTAIN-ROD.

1,250,190.

Specification of Letters Patent. Patented Dec. 18, 1917.

Application filed February 14, 1916. Serial No. 78,190.

To all whom it may concern:

Be it known that I, CHARLES W. KIRSCH, citizen of the United States, residing at Sturgis, in the county of St. Joseph and 5 State of Michigan, have invented certain new and useful Improvements in Curtain-Rods; and I do hereby declare the following to be a full, clear, and exact description of the invention, such as will enable others 10 skilled in the art to which it appertains to make and use the same.

My invention relates to improvements in curtain rods or fixtures, and more particularly to that class of curtain fixtures which 15 include substantially U-shaped curtain rods adapted to be horizontally disposed to project into the room from the window casing. It has for its main object to provide a device of the character set forth which may 20 be easily and quickly built up or assembled from a minimum number of parts which are interchangeably engageable with each other to produce curtain fixtures of different lengths; either single or double; and of 25 varying projection from a window-frame or the like.

Heretofore curtain rods or fixtures of the telescopically adjustable variety have generally been made of two pieces each having 30 an end portion or arm extending substantially at right angles to the middle portion. These rods or fixtures are variable in length only, but not in degree of projection from the window casing or the like.

Fixtures each comprising two of the curtain rods disposed in parallelism one within the other have also been manufactured and sold in large quantities.

In order to supply all demands the dealer 40 has been obliged to carry in stock a relatively large variety of such curtain fixtures varying as to size, style and depth and this has proved a hardship in many instances as, in different localities various styles are particularly popular and other styles practically 45 unsalable. The latter would consequently become shop-worn in time besides unnecessarily tying up the dealer's investment therein. It has also proved a hardship in a lesser 50 degree on the manufacturer.

The object of my present invention is to overcome this hardship on the dealer by so constructing the fixtures as to enable the dealer to easily, quickly and without waste of material, make up rods to suit the patron's 55 tastes and requirements, from a comparatively small stock of component parts separately purchasable from the manufacturer. Thus the small dealer is placed on an equal footing with the larger in so far as his 60 ability to supply a variety of needs from his stock is concerned.

My invention consists in the features of construction and the arrangements and combinations of parts whereby I am enabled to 65 obtain the above mentioned and other objects and all as hereinafter described and particularly pointed out in the appended claims.

My invention will be more readily understood by reference to the accompanying drawings forming part of this specification and in which—

Figure —1— is a fragmentary perspective view of a double curtain rod shown in supporting position and embodying my invention in one form;

Fig. —2— is a fragmentary horizontal section on the line 2—2 of Fig. —1—;

Fig. —3— is a horizontal section similar 80 to Fig. —2— showing two positions of a rod relative to the window, one being in dotted lines;

Fig. —4— is a perspective view of one of the angle brackets or end members as it 85 appears from the inside;

Fig. —5— is a vertical section of the bracket on the line 5—5 of Fig. —4—;

Fig. —6— is an enlarged vertical section taken on the line 6—6 of Fig. —2— showing 90 the fixture which supports the curtain rod;

Fig. —7— is an enlarged inside elevation particularly illustrating the means by which I make the rod proper extensible;

Fig. —8— is a vertical section of the supporting fixture on the line 8—8 of Fig. —6—;

Fig. —9— is a fragmentary vertical section on the line 9—9 of Fig. —2— particu- 100

larly illustrating the means of clamping the rod within the end members and the extension coupler; and

Fig. —10— is a vertical section on the line 5 10—10 of Fig. —9—.

While I have illustrated my invention as being applied particularly to the production of what is termed a flat curtain rod, it will be obvious that many of the features of my 10 invention could be as well embodied in other forms of rods without departing beyond the scope thereof.

In said drawings, A indicates extensible straight curtain rods, B indicates the bracket 15 which I use with the rods A, and C is a supporting fixture which is secured upon the window casing or other suitable support and upon which the curtain rods are removably mounted. In the illustrated embodiment of my invention, I have shown the 20 brackets or end members B as being formed of a channel or C-shaped bar which is bent between its ends to substantially a right angle having one leg D thereof shorter than the opposite leg E. The cross section 25 of the bracket, as best shown in Fig. —10—, is of C-shape, that is, it is provided with inwardly turned parallel flanges F at one side which extend toward each other. These flanges, 30 as shown, are on the inside of the bracket, the outer side of the bracket being continuous and solid. The free ends of the two legs are each provided with holes or openings G in both their top and bottom edges. 35 These holes G are spaced a short distance from the free ends of the brackets and are adapted to receive prongs H provided upon the supporting plates C. Each supporting plate is formed with outwardly extending 40 plates J having the prongs H at their upper ends. The plates J are adapted to enter the open ends of the brackets B and the prongs H, as stated, enter the holes G and thus hold the brackets B supported in position 45 with their free ends held in contact with the adjacent face of the supporting fixture C. The plates J substantially fill the brackets B at least to such an extent that the lower flange or wall of the bracket 50 engages the lower end of the plate J, when the bracket is raised vertically before the upper flange, is disengaged from the prong H.

The cross section of the curtain rod A is similar to the cross section of the brackets B 55 and is made of such dimensions relatively to the brackets B that the ends of the rod A are received telescopically within the ends of the brackets B and are adapted to closely fit the brackets B. The free ends of all of 60 the rods A are identical with each other and are adapted to fit within all of the ends of the brackets B interchangeably. Consequently, it is not necessary, in assembling the curtain rods, to select any particular bracket 65 to fit any particular end of a curtain rod,

but they are adapted to fit each other interchangeably.

The object of making the brackets B with their ends D and E of different lengths is well brought out in Figs. —2— and —3—. 70 In Figs. —1— and —2—, I have illustrated a double curtain rod, the rods being arranged in the same horizontal plane and the brackets B at each end of the rod being parallel with each other. The inner bracket 75 in each case has its shorter end D mounted upon the supporting fixture and its longer end E receiving the curtain rod A, while the outer brackets have their longer ends E mounted upon the supporting fixture C and 80 their shorter ends D receiving and supporting the curtain rod A. The two rods are thus supported in parallel relation, one farther from the window than the other, and are adapted to receive and support fabric curtains of different texture as is quite common at the present time. In Fig. —3—, however, I have shown another use of my unique bracket B. In this instance I have shown in full lines the brackets B with their 85 shorter ends D mounted upon the supporting fixtures C and their longer ends E receiving and supporting the curtain rod A, while in dotted lines, I have shown the brackets having their longer ends E mounted upon the fixture C and their shorter ends D receiving and supporting the curtain rod A, in the latter instance the curtain rod A being positioned at a greater distance from the window than in the former. It will 90 now be clear that a dealer can supply from stock rods of different styles, projections and lengths without the necessity of carrying a lot of different styles and sizes of parts. 95

In making up curtain rods to fit particular windows, the rods are formed of an angle bracket B at each end and a section of curtain rod A¹ supported by and extending between the oppositely disposed brackets. 100 As the ends of the rod A¹ are telescopically received within the ends of the brackets, the rod is, to a certain extent, adjustable in length to accurately fit the place or the window where it is to be used, but obviously 105 this adjustment is quite limited. It is, of course, feasible to use a continuous piece of the rod A¹ extending from one bracket B to the opposite bracket, but I prefer to build up the rod of two or more pieces of the rod 110 A¹ connected together by means of the telescopically fitting union or connector A². The connector A² is in cross-section similar 115 in shape and size to the ends of the bracket B, that is, it is C-shaped and is adapted to snugly receive the ends of the rod A¹ telescopically within its ends. The connector 120 A² is made of thin sheet metal similar to the metal of which the brackets B and the rod A¹ are made and it may be made of such 125 130

a length that I can adjust the curtain rod A several inches longitudinally, as clearly shown in Fig. —2—.

In order to hold the rods A¹ securely within the ends of the brackets B and within the connector A², I provide eccentric expanders K which are formed of flat sheet metal and which are in the nature of flat sheet metal washers adapted to be received within the ends of the rod A¹, I make these washers of shorter diameter in one direction than in the other so that they can be easily placed in position within the ends of the rod A¹ and then by being rotated, so as to bring their longer diameters transversely to the rods A¹, they will forcibly expand the ends of the rods A¹ within the ends of the brackets B or within the ends of the connector A² and thus securely hold the several parts of the complete curtain rod in their adjusted relative positions.

It is to be noted that when I make the brackets B in the form shown in the drawings, I prefer to crush the flanges E and F down tightly upon the body of the bracket at the right angle bend thereof, as best shown in Figs. —4— and —5—, to make the bracket more rigid and stiff.

In making up a curtain rod out of the materials which I have provided, to fit a certain definite window, I first arrange the brackets B to place the rod A at the desired distance or projection from the window. This places the opposing ends of the bracket B a certain definite distance apart and then I may cut a rod A¹ of a length to extend from bracket to bracket and enter the ends of the opposed brackets and be clamped therein, or I may build up the rod out of several pieces of the rod material connecting the pieces together by means of the connectors A² and thus providing a greater adjustability to the rod as a whole.

As many modifications of my invention will readily suggest themselves to one skilled in the art, I do not limit or confine my invention to the specific structures herein shown and described.

I claim as my invention:—

50 1. A curtain fixture comprising wall-fixtures equipped with means for engaging a curtain rod, a curtain rod comprising a middle portion and two L-shaped end members, the arms of which are of respectively different lengths and interchangeably telescopically engageable with said middle portion for varying the spacing of the latter from said wall fixtures, each of said arms interchangeably engageable with said rod-engaging means on said wall fixtures.

60 2. A curtain fixture comprising a pair of curtain rods each consisting of a middle portion and two angular end-members, the several arms of each of the latter being of respectively different lengths, the respective

arms of each of said end-members being interchangeably engageable with said middle portions, and wall-fixtures for engaging the ends of the free arms of said end-members, all of said arms of the latter being interchangeably engageable with said wall-fixtures, said means on said wall-fixtures for engaging one arm of each of two of said end-members being spaced apart, the middle portions of said rods being spaced from each other a distance equal to the difference in length of the respective arms of one of said end members.

3. A curtain fixture comprising a pair of curtain rods each consisting of a middle portion and two angular end-members, the several arms of each of the latter being of respectively different lengths, the respective arms of said end-members being interchangeably engageable with said respective middle portions to vary the distance of the said middle portions from the ends of the free arms of the end members engaged therewith, and wall-fixtures for engaging the ends of the free arms of said end-members, all of said arms of the latter being interchangeably engageable with said wall-fixtures, said means on said wall-fixtures for engaging one arm of each of two of said end-members being spaced apart a distance equal to the difference in length of the respective arms of one of said end members, the long arms of one and the short arms of the other pair of the latter being respectively engaged with said middle portions, and vice versa the other arms thereof engaged with said wall fixtures.

4. An extensible curtain rod comprising a rod proper made up of a plurality of pieces of rod of C-shaped cross-section, sleeves of C-shaped cross-section telescopically receiving the adjacent ends of said pieces, means for clamping the sleeves upon said pieces, in combination with right angled end members having ends which are duplicates of each other and adapted to telescopically receive the free ends of said rod proper.

5. A curtain rod including a middle portion and end members adapted to be engaged with each other and with wall fixtures, said end members each having a long arm and a short arm adapted to be interchangeably engaged with said middle portion and said wall fixtures for spacing the middle portion at two different distances from the wall.

6. A curtain hanger comprising a rod, a pair of end members each having a long and a short arm extending substantially transversely to each other, and a pair of wall fixtures adapted to be secured to a window casing, the respective arms of said end members adapted to be interchangeably engaged with said rod and said wall fixtures respectively for spacing the rod at different distances from said wall fixtures.

7. A U-shaped curtain rod comprising a middle portion and two integral angular end members telescopically engaged with said middle portion, said end members providing means whereby the spacing of the middle portion of the rod from the window casing or the like may be varied.

In testimony whereof I have signed my name in presence of two subscribing witnesses.

CHARLES W. KIRSCH.
